UNITED STATES PATENT OFFICE.

LOUIS COURTOT, OF PARIS, FRANCE, ASSIGNOR TO AMERICAN RADIATOR COMPANY, OF CHICAGO, ILLINOIS, A CORPORATION OF NEW JERSEY.

DESIGN FOR A RADIATOR-SECTION.

57,818.

Specification for Design.

Patented May 10, 1921.

Application filed August 30, 1919. Serial No. 320,954. Term of patent 14 years.

To all whom it may concern:

Be it known that I, LOUIS COURTOT, a citizen of the Republic of France, residing at the city of Paris, in the Republic of France, have invented and produced a new, original, and ornamental Design for a Radiator-Section, of which the following is a specification, reference being had to the accompanying drawings, forming part thereof.

In said drawings,

Figure 1 is a face view or front elevation of a radiator section embodying or incorporating my said design;

Fig. 2 is an end or edge view;

Fig. 3 is a top view;

Fig. 4 is a vertical sectional view, on the line 4—4 of Fig. 1, showing the contours

of the top and bottom headers and the intermediate connecting member, and the vertical arrangement of the columns or tubes with respect thereto, and

Fig. 5 is a transverse sectional view, on the line 5—5 of Fig. 1, showing the contour or outline of the vertical tubes or columns with reference to the horizontal outlines of the intermediate connecting member, and the top and bottom headers.

I claim:—

The ornamental design for a radiator section, as shown.

LOUIS COURTOT.
